H. J. ELEY

CENTRIFUGAL APPARATUS FOR SPINNING ARTIFICIAL SILK AND VISCOSE

Filed April 19, 1927

Inventor

H. J. Eley

By *John Lawrence Atty.*

UNITED STATES PATENT OFFICE.

HARRY JOHN ELEY, OF SUTTON COLDFIELD, BIRMINGHAM, ENGLAND.

CENTRIFUGAL APPARATUS FOR SPINNING ARTIFICIAL SILK AND VISCOSE.

Application filed April 19, 1927, Serial No. 184,979, and in Great Britain March 15, 1926.

These improvements have more particularly to do with the method of mounting the spinning box and arranging the rotor.

According to this invention the spinning 5 box or centrifuge can be mounted directly on the end of the motor shaft (or a shaft driven from the motor) and driven at the required speeds without any appreciable or detrimental oscillation.

- 10 The spinning box and the rotor shaft are arranged in such a manner that the spinning box itself is free to adjust itself so that there is no undue vibration even whilst coming up to speed or at the required speeds.
- 15 In addition, the spindle and spinning box are arranged so as to facilitate the withdrawal and replacement of the box under the abnormal conditions obtaining in practice.
- 20 The invention consists more particularly of an original design of spinning box together with an original design of rotor spindle.

The spinning box is designed in such a manner that the centre of gravity is low to 25 permit the box to sit freely on the end of the shaft. The drive is taken from a pin across the top of a dome engaging in a slot on the domed end of the rotor shaft so that the box is free to adjust itself and thus come 30 up freely and rotate freely about the true axis of spin.

The rotor is free to oscillate in any direction and its shaft may be vertical or it may 35 drive a vertical shaft in which case it may be at right angles to the shaft axis.

I will now describe my invention with 40 reference to the accompanying drawing, which shows a construction in which the spinning box is mounted on the vertical extension of a rotor spindle. The drawing is largely in section.

The base plate 1 supports the rotor 2 through the intermediary of a thrust ball bearing 3 and ring bearing 4 over which is 45 a dust cover 5. The spindle 6 of the rotor is extended and carries a partly spherical head 7 on which the spinning cup 8 rests in ball and socket fashion. A slot 9 is made across the head 7 and receives a pin 10 from 50 the underside of the cup and by which rota-

tion of the spindle is communicated to the cup without impairing the ball and socket movement.

The spindle 6 passes through a floating bearing 11 carried on a cylindrical bracket 55 12 by blade springs 13.

This bracket is shown with an opening through which the spindle, rotor, and its bearings can be lifted when the cover 14 is released. This permits easy replacement of 60 parts.

The cup 8 has a low centre of gravity and can be simply lifted off and replaced as required. The connection between the spindle and the cup is such that the latter is free 65 to incline in any direction but will rotate with the spindle and will vertically adjust itself even as the spindle comes up to speed; in addition to which vibrations in the spindle are largely damped out by the free relative, other than rotary, movements of the 70 spindle and the cup.

What I claim is:—

1. In centrifugal apparatus for spinning artificial silk and viscose, a cup mounted on 75 a spindle in ball and socket manner with a slot and pin for conveying the rotation of the shaft to the cup.

2. Centrifugal apparatus for spinning artificial silk and viscose according to claim 1, 80 in which the spindle is an integral extension of that of a rotor the axis of which is vertical.

3. Centrifugal apparatus for spinning artificial silk and viscose in which a cup is 85 mounted on the ball or dome-shaped end of a vertical shaft and is rotatably connected thereto in pin and slot manner but has otherwise free relative movement.

4. Centrifugal apparatus for spinning artificial silk comprising in combination a cup, having a rounded socket on its under side, a pin extending across the socket, a vertical spindle under the cup and furnished with a rounded end to enter the socket, said rounded end having a slot to engage the pin in the socket.

5. Centrifugal apparatus for spinning artificial silk comprising a base, a bearing in the base, an electric motor supported on its 100

vertical spindle by the said bearing, an extension of the said spindle above the motor, a bearing enclosing the said extension, resilient means supporting this bearing in a bracket, a further extension of the spindle above the bracket, a rounded upper end to the said further extension, a slot across the

rounded end, a cup above the rounded end and having a rounded socket on its under side and fitting over the rounded end of the spindle with a pin across the socket engaging in the slot. 10

In testimony whereof I affix my signature.
HARRY JOHN ELEY.
